RAILWAY SIGNALING SYSTEM

Filed June 27, 1929

UNITED STATES PATENT OFFICE

CHARLES A. BROOKS, OF SWISSVALE, AND HARRY C. VANTASSEL, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA

RAILWAY SIGNALING SYSTEM

Application filed June 27, 1929. Serial No. 374,068.

Our invention relates to railway signaling systems of a type involving signals controlled by track circuits.

One feature of our invention is the provision of means for preventing an undesirable momentary operation of a signal when a light engine or a car passes at high speed from one track section to another if the track relay for the rear section closes before the track relay for the forward section opens.

We will describe one form of signaling system embodying our invention, and will then point out the novel features thereof in claims.

15 The accompanying drawing is a diagrammatic view showing one form of signaling system embodying our invention.

Referring to the drawing, reference characters 1 and 1^a designate the track rails of a stretch of railway track which is divided by insulated joints 2 into a plurality of track sections, only three of which sections, C—D, D—E and E—F, are here shown. Each of these track sections is provided with a track circuit which is supplied with current by a battery 3 connected across the rails adjacent one end of the section, and includes a track relay designated by the reference character T with a distinguishing exponent and connected across the rails adjacent the opposite end of the section.

Located adjacent points C and E are signals designated by the reference characters S^c and S^e, respectively, each of which governs eastbound traffic, that is, traffic moving toward the right as shown in the drawing. Each of these signals is of the light type, and, as here shown, is of what is known as the searchlight type signal. Each of these signals comprises a member 6 mounted to oscillate and controlled by two windings 7 and 8. The member 6 carries three roundels G, R and Y arranged to co-operate with an electric lamp 9 in such manner that when the member 6 is in its middle position, to which it is biased, roundel R is in front of lamp 9, whereas, when the member 6 is swung to the left or to the right, roundel Y or roundel G is placed in front of the lamp 9. As shown in the drawing, the lamp 9 is above the roundels but the lamp is placed in this location for purposes of illustration only, and in actual practice it is understood that the lamp is located directly behind the roundels. Each signal indicates "proceed," "caution," or "stop" according as its roundel G, Y or R is located in front of its lamp 9. Operatively connected with the member 6 of signal S^c are two contacts 4 and 5, which contacts are operated in such manner that when the signal is in its "stop" position contact 4 connects with its point 4^b and contact 5 connects with its point 5^b, whereas when the signal is in its "proceed" position contact 4 connects with its point 4^a and contact 5 connects with its point 5^a. A signal of the type thus described is disclosed and claimed in Reissue Letters Patent of the United States No. 14,940, granted to Eli J. Blake on August 31, 1920.

Associated with signal S^e are two relays designated by the reference characters M and P, respectively. Each of these relays is constructed to be slow-releasing so that it will not open its front contacts when signal S^e changes from the caution to the proceed position or conversely. Relay M is so controlled as to be energized when track section D—E is unoccupied while signal S^e is indicating caution or proceed only. Relay P is provided with directional stick control for selecting between opposing and following train movements in such systems as those of the well known absolute permissive block signaling type. When relay P is de-energized signal S^c is controlled by traffic conditions in advance of signal S^e as well as in the rear of signal S^e, whereas when relay P is energized, signal S^c is controlled by traffic conditions in the rear only of signal S^e. Relay P is provided with a pick-up circuit which becomes energized when a train enters section D—E while signal S^e is indicating caution or proceed and while relay M is energized. Relay P then continues energized while relay M is de-energized or signal S^e is indicating stop. When a train travels in the opposite direction, signal S^e

moves to its stop position, de-energizing relay M before section D—E is occupied, and hence relay P will not become energized when the train enters section D—E.

5 Winding 7 of each of the signals S^c and S^e is constantly supplied with current from a suitable source which is not shown in the drawing but the terminals of which are designated B and O. Winding 8 of signal S^c is controlled by track relays T^1 , T^2 and T^3 , and by relays M and P. Signal S^e is controlled by track relay T^3 , and can also be controlled by apparatus associated with the signal next in advance of signal S^e similarly to the manner in which signal S^c is controlled by relays M and P which are associated with signal S^e .

As shown in the drawing, each of the track sections C—D, D—E and E—F is clear and signals S^c and S^e are indicating proceed. 20 Since signal S^e is indicating proceed, contact 4 operated by signal S^e connects with its point 4^a. With contact 4—4^a of signal S^e closed and with relay T^2 energized, relay M is energized by its circuit passing from terminal B, through contact 4—4^a, contact 10^a of relay T^2 , and the winding of relay M to terminal O.

25 Winding 8 of signal S^c is now energized by a circuit passing from terminal B, through contact 11 of relay M, contact 12 of relay T^3 , contact 13^b of relay P, contact 14 of relay T^2 , contact 15 of relay T^1 , winding 8 of signal S^c , and contact 16^b of relay P to terminal O. By means of this circuit, relay P being de-energized, signal S^c is controlled by traffic conditions in advance of signal S^e as well as by traffic conditions between signals S^c and S^e .

30 I will now assume that an eastbound train enters sections C—D, de-energizing relay T^1 . 40 Relay T^1 , upon becoming de-energized opens its contact 15, thereby breaking the circuit for signal S^c and causing signal S^c to move to its stop position.

When the train enters section D—E, de-energizing relay T^2 , relay P becomes energized by its pick-up circuit which passes from terminal B, through contact 4—4^a of signal S^e , contact 10^b of relay T^2 , contact 17 of relay M, and the winding of relay P to terminal O. After a brief period, relay M, being de-energized by the opening of contact 10^a, releases its contacts 17 and 11. After the pick-up circuit for relay P is thus opened at contact 17 of relay M, relay P continues energized by its stick circuit which passes from terminal B, through contact 18 of relay M, contact 19 of relay P, and the winding of relay P to terminal O.

45 When the train enters section E—F, de-energizing relay T^3 , signal S^e is operated to its stop position due to the opening of contact 20 which breaks the circuit for winding 8 of signal S^e . Signal S^e , upon being operated to its stop position, completes a second stick circuit for relay P, passing from terminal B,

through contact 4—4^b of signal S^e , contact 5—5^b of signal S^e , contact 19 of relay P, and the winding of relay P to terminal O.

When the train leaves section D—E, winding 8 of signal S^c is supplied with current of reverse polarity by a circuit passing from terminal B, through contact 16^a of relay P, winding 8 of signal S^c , contact 15 of relay T^1 , contact 14 of relay T^2 , and contact 13^a of relay P to terminal O. Signal S^c now moves to the caution position. It will be noted that as already pointed out, when relay P was de-energized winding 8 of signal S^c was controlled by traffic conditions in advance of signal S^e but that now, with relay P energized, signal S^c is controlled by traffic conditions between signals S^c and S^e only.

When the train moves out of the first block to the right of signal S^e , permitting signal S^e to move to its caution position, signal S^e closes its contact 5—5^a causing relay M to be energized by a circuit passing from terminal B, through contact 4—4^b of signal S^e , contact 5—5^a of signal S^e , contact 10^a of relay T^2 , and the winding of relay M to terminal O. With signal S^e now indicating caution, and with relay M energized, both stick circuits for relay P are open and hence relay P opens its contacts 13^a and 16^a and closes its contacts 13^b and 16^b thus again completing the normal operating circuit for signal S^c . Signal S^c now moves to the proceed position.

It should be pointed out that with apparatus comprising our invention, relay P becomes energized before an eastbound train arrives at signal S^e , and hence in the event of a vehicle such as a light engine or a car passing signal S^e at high speed and so permitting relay T^2 to close its contact 14 before contact 12 of relay T^3 opens, the possibility is removed of signal S^c being operated to its proceed position at this time and displaying the proceed indication for the brief period before contact 12 of relay T^3 opens.

Although we have herein shown and described only one form of signaling system embodying our invention, it is understood that various changes and modifications may be made therein within the scope of the appended claims without departing from the spirit and scope of our invention.

Having thus described our invention, what we claim is:

1. In combination, two successive railway track blocks, a signal for the forward block controlled by traffic conditions in said block, a signal for the rear block responsive to reversals of polarity of the current supplied thereto, a slow-release relay controlled by said forward block signal and by traffic conditions in said rear block, a stick relay, a pick-up circuit for said stick relay controlled by said slow-release relay and by traffic conditions in the rear of said forward block signal, a stick circuit for said stick relay con-

trolled by said slow release relay, and means controlled by pole-changing contacts of said stick relay for supplying said rear block signal with current of normal or reverse polarity.

5 2. In combination, two successive sections of railway track, a signal responsive to reversals of polarity of the current supplied thereto, a slow-release relay controlled by traffic conditions in each of said sections, a stick relay, a pick-up circuit for said stick relay controlled by said slow-release relay and by traffic conditions in the rear section, a stick circuit for said stick relay controlled by said slow-release relay, and means controlled by
10 pole-changing contacts of said stick relay for supplying said signal with current of normal or reverse polarity.

15 3. In combination, two successive sections of railway track, a signal responsive to reversals of polarity of the current supplied thereto, a slow-release relay energized when both of said sections are clear but de-energized when either of said sections is occupied, a stick relay, a pick-up circuit for said stick relay energized when the rear section is occupied while a front contact of said slow-release relay is closed, a stick circuit for said stick relay controlled by a back contact of said slow-release relay, and means for supplying
20 said signal with current of normal or reverse polarity according as said stick relay is de-energized or is energized.

25 4. In combination, a section of railway track, a signal responsive to reversals of polarity of the current supplied thereto, a slow-release relay controlled by traffic conditions in advance of said section as well as in said section, a stick relay, a pick-up circuit for said stick relay controlled by said slow-release relay and by traffic conditions in said section, a stick circuit for said stick relay controlled by said slow-release relay, means controlled by traffic conditions in advance of said section and by a back contact of said stick
30 relay for supplying said signal with current of normal polarity, and means controlled by a front contact of said stick relay for supplying said signal with current of reverse polarity.

35 5. In combination, a first and a second section of railway track, a signal responsive to reversals of polarity of the current supplied thereto, a stick relay, a pick-up circuit for said stick relay, means for energizing said pick-up circuit when said first section is unoccupied while said second section is occupied, a stick circuit for said stick relay, means for energizing said stick circuit when said second section is occupied, and means controlled by said stick relay for supplying said signal with current of one polarity or the other.

In testimony whereof we affix our signatures.

CHARLES A. BROOKS.
